United States Patent Office.

ALPHA A. AETHERTON, OF WATERBURY, VERMONT.

Letters Patent No. 79,095, dated June 23, 1868.

IMPROVED WASHING-MACHINE.

The Schedule referred to in these Letters Patent and making part of the same.

TO ALL WHOM IT MAY CONCERN:

Be it known that I, ALPHA A. AETHERTON, of Waterbury, in the county of Washington, and State of Vermont, have invented a new and useful Improvement on a Washing-Machine; and I do hereby declare that the following is a full, clear, and exact description of the construction and operation of the same, reference being had to the annexed drawings, making a part of this specification, in which—

Figure 1 is a perspective view, with one of the standards removed, with a part of one side of the box, to exhibit more clearly the two wash-boards inside.

Figure 2 shows the knuckles on the under side of the wash-board D, and the upper side of the wash-board E, with rollers perforated with small holes.

Figure 3 is a side view of both wash-boards, showing the ends of the rollers, and a few of the knuckles, all referring to Drawings No. 2.

A, fig. 1, is a water-tight box, three feet eight inches long, twelve inches deep, and twenty inches wide, on legs, so that it stands two feet from the ground. B B are the standards in the middle of the box, attached to the top of the side-boards, (one only being seen in Drawings No. 2,) eighteen inches high from top of the box, which standards support the arms C C, that hold the wash-board D, having a slot in the upper ends of each, by which they are held up by a cross-bar, F, allowing a free vertical motion, so that any thickness of cloth may be laid between the wash-boards. The upper wash-board D is sufficiently convex to describe the arc of a circle, of which the arms are a radius. The under side is set with knuckles, one and a half inch in diameter, and three-fourths of an inch apart, and these are fastened into the board with screws. The lower wash-board E consists of rollers fastened in a side-board at the ends, and the rollers are one and one-fourth inch in diameter, and one-fourth of an inch apart. Each roller is perforated with holes, bored at right angles with its length, and one-fourth of an inch in diameter, and so numerous as to allow the water to pass freely through the rollers. The whole is made of wood at a small cost. The lower wash-board E is sufficiently concave to fit the upper board with knuckles.

The machine is operated by first filling the box A with water until it touches the rollers. Then the garment to be washed is laid upon the rollers, and the upper board D brought down upon it, and moved backward and forward by taking hold of the cross-bar G. Both wash-boards are of the same width as the inside of the box, and the lower one is held in place by wooden pins at each end.

What I claim as my invention is—

The combination of the board D with the knuckles, and the board E with rollers containing holes, which allow the water to flow freely through them, as and for the purpose specified.

ALPH. A. AETHERTON.
